UNITED STATES PATENT OFFICE.

JOHN MILLS, OF WYOMING, NEW JERSEY, ASSIGNOR TO WESTERN ELECTRIC COMPANY, INCORPORATED, OF NEW YORK, N. Y., A CORPORATION OF NEW YORK.

RECORDING AND REPRODUCING SYSTEM.

Application filed April 23, 1924. Serial No. 708,372.

This invention relates to recording and reproducing systems such as phonograph record making or radio broadcast reproducing systems, and particularly, to systems for 5 electrically recording speech or music produced in studios.

In auditoriums sound proceeds from the source and strikes the boundaries of the room where it is partly reflected and travels out 10 until it reaches another surface where it is again partly reflected. At each impact some of the energy of the sound is absorbed or transmitted by the surface so that the reflected sound is weaker than the original. 15 The result is that a succession of tones of diminishing intensity are produced which affect the listener's ear so as to give him the impression that the original sound dies out slowly. This effect is called reverberation 20 and is evidenced by the persistence of the sound after the emission of the sound by its source has ceased. In the study of the acoustics of auditoriums, it has been found that a considerable time of reverberation is 25 desirable for music, since the blending of the tones produces a pleasant effect.

In the making of phonograph records, radio broadcasting, and the like it is often desirable to produce music in small rooms or 30 studios. In such rooms the walls are so close to the source of the sound that if natural reverberation were permitted, the reflected sounds would follow each other in such rapid succession that a confusion of tones rather than a pleasant blending would result. It 35 is, therefore, the usual practice to provide the studios with draperies that absorb rather than reflect the sound. While, by a proper arrangement of the draperies, the room may be made to have a desired time of reverberation this does not cause the studio to simulate the acoustic properties of a large auditorium. For one reason the distance of the auditor to the reflecting surfaces is so small that the 40 component sounds follow each other in such rapid succession that an entirely different effect is produced than in an auditorium where the distances are much greater. The result is that when music such as orchestral 45 music which one is accustomed to hear produced in large halls is produced in a studio the effect is unnatural.

It is an object of this invention to improve the quality of music produced in 50 studios.

It is a further object of this invention to simulate in music produced in small rooms the effect and quality of music produced in large halls.

It is a further object of the invention to 55 provide electrical means for producing artificial reverberation in music produced under conditions which tend to eliminate natural reverberation.

In accordance with this invention the 60 quality of music produced in acoustically dead rooms is improved by producing artificial reverberation. As is well understood by those skilled in the art, artificial transmission lines cause both an attenuation and 65 a phase shift. If they are so designed that the phase shift is proportional to the frequency the wave is not distorted but merely delayed in time of transmission. It is therefore proposed to make use of these properties 70 of artificial lines for producing reverberation in recorded music. In one form this invention comprises an electric recording system 75 with artificial lines for producing reverberation.

A feature of this invention consists in transmitting waves over an artificial line reflecting them at the distant end and transmitting them back thus obtaining twice the 80 phase shift on delay which could be obtained by transmitting them over the line in only one direction.

A further feature of the invention consists in amplifying the waves at the distant end in connection with this reflection. 90

This invention will be more readily understood by reference to the following description in connection with the drawing in which: Fig. 1 shows diagrammatically, one embodiment of the invention in which reverberation is produced by the reflection of electric waves in an artificial line. Fig. 2 shows a second embodiment which employs a standard 21 type repeater circuit in connection with an artificial line. Fig. 3 shows 100 a third embodiment which employs a series of parallel paths comprising artificial lines of different length.

The description of Figs. 1 and 2 which follows will be more readily understood after 105 referring to the following description of Fig. 3. There is shown a transmitter 5 on which the sound is impressed. Connected to this is an amplifier 6, and to the output of the amplifier are connected various parallel 110

paths 7, 8 and 9. Amplifiers 10, 11 and 12 are connected in these paths. Paths 7 and 8 are provided with artificial lines 13 and 14, respectively. The terminals of these lines 5 are connected to the amplifiers 15 and 16, respectively, while an amplifier 17 is provided at the far end of the path 9. The outputs of the amplifiers 15, 16 and 17 are connected in parallel through the transformer 18 to a recorder 19 which may be, for example, a phonograph recorder, a loud speaking telephone receiver, a radio broadcasting circuit or other device, by means of which it is desired to reproduce the music impressed 10 on the transmitter 5.

Part of the waves produced by the transmitter passes directly through path 9 to the recorder, while other parts pass through the two parallel paths 7 and 8. The phase 20 shifts of lines 13 and 14 are so adjusted that the waves flowing through them arrive at the recorder later than the waves flowing through the path 9. The attenuation of the lines and the degree of amplification of the 25 amplifiers are so adjusted as to make the amplitude of the waves flowing through the lines smaller than the amplitude of waves passing through path 9. These component currents decreasing in amplitude and lagging 30 in phase produce an effect in the recorder similar to that which would be produced by a natural reverberation in an auditorium.

It is evident that as many parallel paths 35 may be used as desired giving any desired number of component currents. Since it is often advantageous to be able to regulate the reverberation to suit the type of music recorded and the type of hall it is desired to 40 simulate, it may be desirable to use artificial lines of the variable type such as those disclosed in my United States Patent No. 1,628,992, issued May 17, 1927, and so permit the time interval and rate of decay of the 45 reverberations to be adjusted to suit the individual requirements of each recording.

In the embodiment shown in Fig. 1 a transmitter 21 is connected through a transformer 22 to an amplifier 23, the output of 50 which is connected through a second transformer 24 to a potentiometer 25. Connected to the potentiometer are two parallel paths, one comprising an amplifier 26, the output of which is connected to the recorder 29 and the other comprising an artificial line 27, the terminal 28 of which is left open.

The wave flows from the transmitter through the first amplifier to the potentiometer where it divides between the two 60 parallel paths, part going from the amplifier 26 to the recorder 29, the other part passing into the artificial line 27. This part flows through to the open terminal where it is reflected back through the line, being attenuated and retarded in phase as it passes

in each direction. When the reflected wave reaches the potentiometer 25, part divides between the input circuit of the amplifier 26 and the output circuit of the amplifier 23 and part is reflected back into the artificial 70 line, which is so constructed that its impedance does not match the impedance of the potentiometer. The current which passes into the output circuit of the amplifier 23 is dissipated, while that which passes into 75 amplifier 26 is amplified and passes on to the recorder 29. This current is smaller in amplitude than, and lags behind, the original current flowing into the recorder. That part of the wave which is reflected back into 80 the line repeats the cycle followed by the first wave flowing into the line, thus causing a third component current to flow into the reproducer. This third current is still smaller in amplitude and still further lags 85 behind the original current. In this way a series of component currents each decreasing in amplitude and each lagging behind the other are produced.

In Fig. 2 a transmitter 31 is connected to a 21-type (two-way, one element) repeater circuit 32 which is, in turn, connected through an artificial line 33 to a second 21-type repeater circuit 34 and thence through an amplifier 35 to a recorder 36. Part 90 of the current coming from the transmitter 31 is transmitted directly to the artificial line 33, but the larger part divides between the input and output circuits of the vacuum tube amplifier 37. The energy which flows 100 into the output circuit is lost. The wave flowing into the input circuit is amplified and the amplified current passes to the output coil 38 where it divides between the transmitter circuit and the artificial line, 105 half going to each, if the impedances of 31 and 33 are balanced which must be substantially the case in order to avoid singing. The energy of that half which passes into the transmitter circuit is dissipated, while 110 the wave flowing into the artificial line goes to the repeater 34 where it is amplified and the amplified current passes to the output coil where it divides between the recorder circuit and the artificial line. The wave 115 which flows back into the artificial line is amplified by repeater 32 and half of the amplified current dissipated in the transmitter circuit, while the other half passes into the artificial line and is amplified by repeater 34, half of the amplified current 120 passing back into the artificial line to repeat the cycle, while the other half flows into the reproducer circuit. This last current lags behind the original and is of smaller 125 amplitude due to the phase shift and attenuation of the artificial line and so appears as the first reflection. Part of the current which flows back into the line is also finally impressed on the reproducer after having 130

been retarded and attenuated. Thus, we have a series of currents in the reproducer 36, each one lagging the preceding one by a definite time and decreasing in amplitude 5 in a logarithmic ratio until the last is inappreciable.

It is evident that in order that this circuit be operative, it is necessary that the attenuation of the artificial line be greater than the 10 effective amplification of at least one of the repeater circuits. To any other extent the phase shift and attenuation of the line and the amplification of the repeaters may be adjusted to give the desired effect.

15 As pointed out above this invention is widely applicable to various systems for recording and reproducing sound and it should be understood that the terms recording system and recorder as used in this description 20 and the appended claims are meant to include all such systems and devices.

Many embodiments of the invention will readily suggest themselves to those skilled in the art and the invention is not limited 25 to the three examples shown.

What is claimed is:

1. In combination, means for producing waves corresponding to sound and a phase shifting wave transmission system associated 30 therewith for producing artificial reverberation.

2. In combination, a telephone transmitter and an artificial line in circuit therewith for producing the effects of reverberation in 35 the electrical waves.

3. A sound recording system, comprising a telephone transmitter, a recorder and an artificial line for producing reverberation, connected in circuit therewith.

40 4. A sound recording system, comprising a telephone transmitter, a recorder, and means comprising an artificial line for producing reverberation of the recorded sound.

5. A sound recording system, comprising a 45 telephone transmitter, an electrical recorder, and a plurality of wave transmitting paths associated with said transmitter and recorder, one of said paths including an artificial line.

50 6. A sound recording system, comprising a transmitter, a recorder, and a circuit associated with said transmitter and recorder comprising an artificial line, whereby component currents of different phase and amplitude are impressed on said recorder.

7. A sound recording system comprising a transmitter, two paths connected in parallel to said transmitter, an open ended artificial line connected in one of said paths, 60 and a recorder connected in the other of said paths.

65 8. A system for recording sound produced under conditions which tend to eliminate reverberation comprising means for converting the mechanical vibrations which com-

prise the sound into electrical waves, means for reconverting said electrical waves into mechanical vibrations, and means associated with said converting means and said reconverting means for producing the slow dying out of said electrical waves, whereby substantially the same effect is produced in said 70 reconverted vibrations as would be produced had the sound originally been produced under conditions of natural reverberation. 75

9. A system for recording sound produced in acoustically dead rooms comprising a transmitter, a recorder, a variable ratio amplifier, and a variable length artificial line 80 associated with said transmitter and recorder for producing the desired reverberation of said recorded sound.

10. An apparatus for producing a desired degree of change in energy waves comprising a wave transmission system for producing a portion of the desired change, means for impressing the waves on said system, and means for reflecting the waves back through the system to effect another portion of the change, said wave transmission system being proportioned in accordance with the degree of change it is desired to produce. 85

11. In combination, a network for effecting a phase shift on waves transmitted therethrough, a two way one element type repeater associated with said network to amplify and reflect the waves back through 90 said network to multiply the phase shift produced therein. 95

12. In combination, means for converting 100 sound waves produced in an acoustically dead room into corresponding energy waves of a different type, and means associated therewith for modifying the converted waves to simulate natural room reverberation. 105

13. An apparatus for producing a desired time delay in the transmission of energy waves, comprising an artificial line proportioned to produce in a single traverse a predetermined fraction of the desired time delay, means for impressing the waves upon 110 said line, and means at the remote line terminals for retransmitting the received waves back through the line to produce another fraction of the desired delay. 115

14. An apparatus for producing a desired time delay in the transmission of energy waves, comprising an artificial line proportioned to produce in a single traverse a predetermined fraction of the desired time delay, means for impressing the waves upon 120 said line, and means at the remote terminals of the line for amplifying and retransmitting the received waves back through the line to produce another portion of the desired delay. 125

In witness whereof, I hereunto subscribe my name this 21st day of April, A. D. 1924.

JOHN MILLS.
